UNITED STATES PATENT OFFICE.

TANDY A. BRYSON, OF TROY, NEW YORK, ASSIGNOR TO TOLHURST MACHINE WORKS, A CORPORATION OF NEW YORK.

CENTRIFUGAL MACHINE.

Application filed June 12, 1920. Serial No. 388,658.

To all whom it may concern:

Be it known that I, TANDY A. BRYSON, a citizen of the United States, residing at Troy, in the county of Rensselaer and 5 State of New York, have invented new and useful Improvements in Centrifugal Machines, of which the following is a specification.

The invention relates to centrifugal machines and more especially to novel means 10 and devices in the machine designed to compensate for, or take care of, an unbalanced whirling or rotating load, and the objectionable or harmful vibrations which arise or are 15 set up in the machine.

Objects and advantages of the invention will be set forth in part hereinafter and in 20 part will be obvious herefrom, or may be learned by practice with the invention; the same being realized and attained by means 25 of instrumentalities and combinations pointed out in the appended claims.

The invention consists in the novel parts, 25 constructions, arrangements, combinations and improvements, herein shown and described.

The accompanying drawings, referred to herein and constituting a part hereof, illustrate one embodiment of the invention, and 30 together with the description, serve to explain the principles of the invention.

Of the drawings:—

Fig. 1 is a vertical section through an under-driven centrifugal machine embodying the invention; and

Fig. 2 is a vertical section through an over-driven or suspended centrifugal machine embodying the invention.

In loading the baskets of centrifugal 40 machines, it is customary or at least common to put in an unbalanced load. The machines are, therefore, usually constructed with more or less efficient means for taking care of such an unbalanced load during the rotation 45 or whirling of the loaded machine to effect the drying or separating action. When centrifugal machines are equipped to take care of an unbalanced load, the time which otherwise would be spent in trimming the 50 load is saved.

When a centrifugal basket which is

loaded so that it is out of balance (that is, the mass or weight of the load is not symmetrically disposed around the basket spindle or shaft) is rotated, the basket tends 55 to rotate about an axis through its center of mass as so loaded, and this axis does not coincide with the geometrical axis of the machine, which latter axis coincides with the axis of the basket shaft. There is thus 60 imparted to the basket and its shaft a vertical angular oscillation or gyratory motion.

If the basket shaft or spindle were mounted in a rigid bearing, the basket could be compelled or constrained to rotate about its 65 geometrical axis, but this is mechanically impracticable as it would result in excessive strain and wear in the bearings and shaft, and breakage of these and cooperating parts would or might result. 70

In designing and building centrifugals adapted to take unbalanced loads, therefore, the spindle or shaft is supported or journaled so that the basket may rotate about or near to the mass axis of the basket and its 75 unbalanced load. Such a bearing permits the unbalanced rotating basket to depart from its geometrical center of rotation, and at the same time interposes a yielding or resilient resistance to the basket and shaft 80 assuming fully or actually the path of rotation or gyration about the center of mass of the unbalanced load. Such a bearing is constructed and designed to maintain the basket shaft or spindle in an intermediate 85 path or position between the one it would of itself assume due to the unbalanced load and the path or position of balanced running.

A resilient bearing or bearing material, 90 such as is employed for the purpose described, when deflected under the action of a force, tends to return to the normal or un-deflected position. If a force be repeatedly and alternately applied to and removed from 95 such a bearing or material, that is, if the force be intermittently and especially periodically applied to the material, vibrations are set up in the mechanism, which are disturbing and harmful and which may 100 prove destructive. These vibrations will continue until damped out or absorbed by

- internal friction or equivalent resistance in the resilient body itself, or by friction in external bodies which confine or are vibrated by the resilient body.
- 5 Structures or organizations of mechanical parts or elements including such resilient members have a natural period or frequency of vibration, such period or frequency being dependent upon the masses involved, 10 the degree of resilience present and the degree or amount of restraint imposed. If such a structure or organization be subjected to impulses applied with a frequency comparable with the natural frequency just 15 referred to, the effect will be cumulative, and may cause vibrations of increasing force or amplitude until the amount of movement becomes excessive, harmful and possibly destructive.
- 20 Centrifugal machines are subjected during rotation to isochronous impulses due to unbalance of load, the repeated impact from belt lacings, and from other causes, and the frequency of these external impulses 25 changes, especially during acceleration. It frequently happens that for a considerable period of time these external impulses will synchronize with the natural time or period of vibration of the structure or machine, 30 causing the vibrations to "build up" and the machine to "sail."
- The present invention provides a centrifugal machine adapted for unbalanced loads, wherein the basket spindle or shaft is flexibly or resiliently mounted so as to yield to, 35 while at the same time restraining, the tendency of the machine to rotate about its center of mass, and in conjunction and cooperation therewith providing frictionally operating 40 vibration absorbing devices, which eliminate the cumulative effect of the vibrations without materially decreasing or limiting the flexible or resilient action of the mounting.
- The invention provides a regulating or 45 governing device of the kind referred to wherein the weight of the basket and load are carried upon a plurality of superposed contacting friction plates, relatively movable with respect to each other, one plate or 50 set of plates moving with the basket shaft when it oscillates vertically due to unbalanced load, the plates not so moving offering frictional resistance or retardation to the moving plates, and thereby to the shaft, 55 basket and load, the frictional pressure on the plates being created or effected by supporting the shaft, basket and load.
- As embodied, and in accordance with certain features of the invention, a resilient 60 bearing or bearing member is employed and cooperating therewith friction members or parts, such as just described, cooperating together, certain of which move more or less with the bearing while others thereof 65 are stationary. These members or parts are put or maintained in frictional engagement by the weight of the basket and load supported by the bearing, the friction absorbing the vibrations while the resilient bearing permits a proper degree or amount of 70 restrained or yieldingly resisted gyratory motion of the basket and its spindle and its housing with the unbalanced load. The frictional devices are preferably arranged at either side, that is both above and below, the resilient bearing.
- 75 Further in detail, as embodied, a hollow cylindrical resilient member is located within an outer casing and surrounds the basket shaft housing, and above and below this resilient member are a plurality of alternate contacting annular friction plates or discs, one disc fitting the housing and having clearance between it and the external casing and a contacting disc fitting the outer casing and 80 having clearance about the housing.
- 85 The outer casing and the housing have horizontal flanges, and the weight of the basket, spindle and load is transmitted down from the flange of the bearing housing 90 through both the top and bottom series of friction plates and the resilient member to the inwardly projecting flange of the outer casing, which casing is supported on the machine frame. Angular motion of the axis 95 of the bearing housing (the center of which will be about mid-height of the resilient member), due for instance to unbalanced basket load, causes the friction plates or 100 discs to slide over each other, thereby developing the necessary friction to control the gyratory action and to absorb the vibrations.
- 105 Referring now to the structural details of the present preferred embodiment, illustrated by way of example in the accompanying drawings, in Fig. 1, the invention is shown applied to the under-driven type of 110 centrifugal machines.
- 115 Therein the outer casing 1 of the centrifugal is carried on a pedestal or frame 2, and is provided with an inwardly extending top flange 3 and one or more bottom outlets 4, although the casing may be of any suitable form so far as concerns the present invention.
- 120 The basket 5 as shown comprises the cylindrical perforate side wall 6, and the inwardly projecting flange or cap 7 and the bottom 8. Centrally located on the bottom 8 is a hub 14^a, which hub rests upon the top 125 of a basket spindle or shaft 9, shaft 9 being rotated to whirl the basket for the drying or separating operation. Hub 14^a is fastened to shaft 9 in a suitable manner. The driving means for spindle or shaft 9 comprises a belt pulley 10, having its hub 14 fixed to the shaft in a suitable manner as by a clamping screw 12. The driving belt runs over a pulley 13, and a suitable belt shifter, brake and other appliances or fixtures may be added in 130

practice, but are omitted from the drawing for the sake of clearness.

The present invention is embodied and applied herein to the bearing for the spindle or shaft 9, to meet the problems and conditions arising out of unbalanced loading of the basket as already described. As embodied the spindle or shaft 9 is journaled in a housing 15, by any suitable structure or arrangement of parts.

Surrounding housing 15 is a resilient bearing member 20, which is preferably a hollow cylinder of rubber, or other suitable material, embracing or surrounding and preferably closely fitting the housing 15. When the basket and spindle gyrate, that is, when they have vertical angular motion, the central or axial point of such motion will be located about mid height of the resilient member 20, the member 20 yielding to such movement while at the same time yieldingly resisting it and tending to return the shaft to simply or solely its own axial rotation, without any additional or modifying motion.

The resilient member 20 is contained and preferably closely fitted within a casing 21, which casing is preferably formed on or attached to the machine frame, being shown bolted to the foot of pedestal 2.

The cooperating friction devices comprise sets of contacting, relatively movable friction members deriving their frictional action wholly or in part from carrying the weight of shaft 9, basket 5 and the basket load. Preferably there is a set of the friction devices above and another below the resilient member 20.

As embodied, a plurality of horizontally disposed, flat annular plates, preferably of non-resilient material, lie in superposition and in contact one with another, one set above and one below the member 20. A plate 22 has its external periphery substantially fitting easily the interior of casing 21, so that it is in fixed position horizontally within the casing, but having clearance about the housing which it encircles.

Contacting with plate 22 on the under side thereof is an annular plate 23, with its inner periphery fitting easily the exterior of the housing but having clearance between its exterior periphery and the interior wall of the casing, so that it will move with any non-rotary motion of spindle 9, and plate 23 will slide on plate 22. A plate 24, which is like plate 22 is shown between plate 23 and the member 20.

On the bottom side of resilient member 20, as embodied, is another set of plates, plates 25 and 27 being like plate 23, and plate 26 being like plates 22 and 24, and operating in the same manner. One set of the plates is one side the center of gyration or vertical angular movement of shaft 9 and

the other set of plates is on the other side of that center, and thus cooperates to dampen and absorb any objectionable or harmful non-rotary motion of the basket shaft 9, the basket and load.

The weight of the basket 5, of its load, and of its spindle or shaft 9, is laid on the parts just described, and for this purpose as embodied, a flange 28 is formed at the top of the housing 15 and rests upon the top friction plate 22. The bottom plate 27 rests upon an internal flange or step 29 formed within the casing 20 and providing clearance about the housing 15. There is thus imparted to the plates sufficient frictional pressure, and an efficient degree of pressure is likewise imparted to the resilient member, while allowing it a degree of possible vertical movement to and fro varying with the load and pressure thereon.

In Fig. 2, the same construction, substantially, is shown applied to a machine of the suspended or over-driven type. Therein the casing 35 is supported upon a frame or the floor, and the basket 36 hangs freely therewithin, being carried at the bottom of its shaft or spindle 37. Shaft 37 at its upper end is provided with a housing, numbered 15 to correspond to the same part in the description of the under driven machine already given. The corresponding parts of the means for governing and damping the non-rotary movements of the shaft have the same reference numerals applied thereto as in Fig. 1 which shows the under-driven machine, and repetition of the description is unnecessary. In this machine casing 21 is supported from beams 30.

Exhaustive and extensive tests under varying actual working conditions have demonstrated a construction according to this invention to be capable of carrying much more unbalanced load with complete safety and freedom from wide whipping or "sailing" of the spindle and its load, and at the same time it eliminates much of the short and jerky vibrations common in the usual type or constructions of such machines.

The resilient member in this construction need not be placed upon fixed and permanent mechanical pressure and constriction as is common in prior constructions. This reduces the rigidity and consequent bearing wear, power consumption and cost of parts and assembly and rubber deterioration. In the old types the rubber is so heavily compressed that it is driven into screw-threads and into all openings and joints until it is difficult to get it into final position, and several re-tightenings must be made after the machine has been run for some time. It is almost impossible to take the bearing apart without cutting out the rubber.

By inserting the proper amount of friction, which may be ascertained by testing

or experience, the vibrations may be damped to eliminate their cumulative effect and the "sailing" of the basket without substantially decreasing the full and desirable flexibility of the spindle mounting.

The invention in its broader aspects is not limited to the specific mechanisms shown and described but departures may be made therefrom within the scope of the accompanying claims without departing from the principles of the invention and without sacrificing its chief advantages.

What I claim is:—

1. A centrifugal machine including in combination a basket and supporting and rotating means therefor including a shaft, a housing in which the shaft is rotatably hung, a cylindrical resilient member about the housing, a casing surrounding the housing, a plurality of non-resilient annular discs within the casing, contacting together and surrounding the housing, some of the discs fitting the housing closely and having clearance with respect to the casing, and other of said discs fitting the casing and having clearance about the housing so as to be horizontally slidably one on another, there being a series of said discs above and another series below the resilient member, the housing being supported by the discs and resilient member.

2. A centrifugal extractor including in combination a basket, a shaft therefor, a bearing for the shaft permitting gyratory movement thereof comprising a housing in which the shaft is journaled, a resilient gyration absorbing member fitting about the housing at its center of gyration and a plurality of radially movable friction members supporting the weight of the basket and shaft away from its center of gyration.

3. A centrifugal extractor including in combination a basket, a shaft therefor, a bearing for the shaft permitting gyratory movement thereof comprising a housing in which the shaft is journaled, a resilient gyration absorbing member fitting about the housing at its center of gyration and a plurality of radially movable friction members supporting the weight of the basket and shaft away from its center of gyration and in turn supported by the resilient gyration absorbing member.

4. A centrifugal extractor including in combination a basket, a shaft therefor, a bearing for the shaft permitting gyratory movement thereof comprising a housing in which the shaft is journaled, a resilient gyration absorbing member fitting about the housing at its center of gyration and a plurality of flat friction discs of different diameters, alternately arranged and relatively movable with respect to one another, supporting the weight of the basket and shaft away from its center of gyration.

5. A centrifugal extractor including in combination a basket, a shaft therefor, a bearing for the shaft permitting gyratory movement thereof comprising a housing in which the shaft is journaled, a resilient gyration absorbing member fitting about the housing at its center of gyration and a plurality of basket and shaft supporting friction discs, one disc moving with the shaft and a contacting disc held against such movement.

6. A centrifugal extractor including in combination a basket, a shaft therefor, a housing in which the shaft is journaled, a member about the housing yielding resiliently radially at and immediately at each side of the center of gyration to absorb the gyratory movement, and basket and shaft supporting friction members contiguous to said yielding member and relatively movable to absorb the gyratory movement.

7. A centrifugal extractor including in combination a basket, a shaft, a casing, a resilient member fitted within the casing about the shaft against radial displacement to constitute a resilient center of gyration, a plurality of friction plates radially slidably one upon and relatively to another, a housing in which the shaft is journaled and a supporting flange carried by the housing, the flange resting on the topmost friction plate.

8. In a centrifugal extractor, a shaft, a supporting bearing therefor comprising an annular collar of resilient material surrounding the bearing and extending above and below the center of gyration, and a plurality of relatively movable friction plates for imposing a frictional retarding force to sidewise movement of the bearing.

9. In a centrifugal extractor, a shaft, a supporting bearing therefor comprising an annular collar of resilient material surrounding the bearing and extending above and below the center of gyration, and a plurality of alternately arranged, relatively movable friction plates of different diameters for imposing a frictional retarding force to sidewise movement of the bearing.

10. In a centrifugal extractor, a shaft, a supporting bearing therefor comprising a deformable resilient element surrounding the bearing and resistant to sidewise or gyratory movement thereof, and a plurality of alternately arranged annular friction plates of different diameters surrounding the bearing and slidably on one another when the shaft moves sidewise or gyrates, for imposing a frictional retarding force to such sidewise or gyratory movement.

11. In a centrifugal extractor, a shaft, a supporting bearing therefor comprising a deformable resilient element surrounding the bearing and resistant to sidewise movement thereof, a plurality of relatively mova-

ble friction plates above the resilient element, and a flange carried by the bearing and resting on the top plate of the plurality of friction plates, for transmitting the weight of the shaft and associated parts thereto.

In testimony whereof, I have signed my

name to this specification, in the presence of two subscribing witnesses.

TANDY A. BRYSON.
